Primary Examiner — Philip S Hyder*(74) Attorney, Agent, or Firm* — Sterne, Kessler, Goldstein & Fox P.L.L.C.**(57) CLAIM**

The ornamental design for a mold for a medical dosage form, as shown and described.

DESCRIPTION

FIG. 1 is a perspective view of the mold for a medical dosage form of the instant invention;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines shown in the figures (portions of the design shown in broken/dashed lines) are included for the purpose of illustrating environment and form no part of the claimed design.

1 Claim, 7 Drawing Sheets**Matter enclosed in heavy brackets [ ] appears in the original patent but forms no part of this reissue; matter printed in italics indicates the additions made by reissue.**(56)
